INDICATOR FOR FINISHING-MACHINE SCREEDS

James E. Bushnell, Aspinwall, Pa., assignor to
 Blaw-Knox Company, Pittsburgh, Pa., a corporation of New Jersey

Application December 2, 1941, Serial No. 421,327

6 Claims. (Cl. 94—45)

This invention relates to an indicator for finishing-machine screeds and, in particular, to a device for indicating the "crown" or degree to which a deformable screed has been forcibly caused to assume a curved condition.

Deformable screeds for finishing machines are well known, a typical form thereof being shown in French Patent 1,995,450. This patent also discloses an indicator intended to show at a glance the extent of deformation of the screed. There are certain objections, however, to the indicator shown in said patent and it is the object of my invention to provide an improved indicator construction which overcomes such disadvantages. Among the latter is the fact that the French indicator is not accurate because the relatively fixed member thereof is mounted on a portion of the screed which is subject to the forces applied to deform the troweling surface, and, though theoretically rigid, is practically deformable even when constructed of heavy members. Such members, furthermore, are not equally deformable in different machines so it is not possible to make a uniform allowance for variation from the true indication. The indicator of the French patent, moreover, moves with the screed which oscillates longitudinally and is, therefore, rather difficult to read during operation.

I have invented a novel indicator for finishing-machine screeds which is not subject to the shortcomings mentioned above. In a preferred embodiment, I provide an indicator including a relatively fixed member mounted on the frame of a finishing machine which, relatively speaking, is quite rigid and not subject to the forces exerted on the screed to deform it to crowned contour. I also provide a relatively movable member or gage cooperating with the fixed member to provide a visible indication. The gage is positioned by the elevation of the screed at a point adjacent the center thereof. I also provide means on the screed for supporting the gage without imparting to the latter the longitudinal movement of the screed.

Further details of the invention and the advantages thereof will be made more apparent during the following complete description which refers to the accompanying drawings illustrating the above-mentioned preferred embodiment. In the drawings,

Figure 1 is a plan view showing certain portions of a finishing machine and its screed with parts omitted for the sake of clearness;

Figure 2 is a sectional view taken along the plane of line II—II of Figure 1 showing the in-

5 dicator, the screed and its supporting structure in elevation;

Figure 3 is a sectional view taken along the plane of line III—III of Figure 2 showing the indicator in side elevation, and

5 Figure 4 is an elevation of a detail.

Referring now in detail to the drawings, the indicator of my invention shown generally at 10 is mounted on a finishing machine which may conveniently be of the general type shown in Ord Patent 1,522,138, including spaced end-frames 11 adapted to travel along the side forms or road rails between which a pavement slab is cast, the end frames being connected by main transverse members such as front and rear beams 12. In the particular form of finishing machine partially shown in the drawings, the members 12 are secured to brackets 13 fastened to the ends of the end frames 11. It will be understood that the finishing machine also includes a power unit such as an internal-combustion engine and the necessary control and transmission devices for driving traction wheels carried in the end frames and for operating a transversely extending screed which is mounted on the machine for reciprocation longitudinally, i. e., transversely of the pavement slab. My invention, however, does not concern such details and they are, therefore, omitted. The screed itself is shown generally at 14 and is 10 preferably of the type disclosed in the French patent aforementioned, including a relatively rigid supporting member 15 and a deformable troweling member 16 therebelow. The supporting member 15 is composed of a pair of channels secured together by cross plates (not shown). The troweling member 16 is also a channel disposed with its flanges upwardly.

The French patent fully discloses the means for deforming the troweling member 16, including 15 tension links, bell cranks and take-up means such as a turn-buckle. Of the latter, only the turn-buckle is shown at 17 and the tension links at 18 and 19. The turn-buckle is supported in a bracket 20 secured to the screed support 15. By 20 operating the turn-buckle 17 in one direction or the other, the troweling member 16 on the screed is forcibly caused to assume a curved condition or is permitted to return to its normal, relatively straight condition, by the means and in the manner fully disclosed in the French patent.

A driving pin 21 extends through the supporting member 15 of the screed at about the mid-point thereof. The pin passes through aligned holes in the webs of the channels forming the member 15 and also in a plate 22 and an auxiliary

channel 23 welded thereto, to provide a bearing of greater length. The rear end of the pin is machined as at 24 for the attachment of a pitman for reciprocating the screed.

The structure described above is known, at least generally, and it now remains to describe in detail the indicator of my invention as applied to the finishing-machine construction outlined above.

A support in the form of a channel 25 extends forwardly from the frame of the machine, being carried on the forward cross-member 12. An auxiliary channel 28 extends laterally from the channel 25 on the upper flange of the beam 12 and is secured to the channel 25 by an angle bracket 27. An auxiliary channel 28 extends laterally from the channel 25, being secured thereto by an angle bracket 29. A plate 30 rests on and is welded to the channels 25 and 28. The channel 28 is connected to another channel (not shown) similar to channel 25 extending forwardly from the front cross-member 12. By virtue of the construction described, the channel 25 is supported from the main frame of the machine which is relatively quite rigid, and is fixed vertically relative to the slab being finished.

A socket 31 is secured to the flange of the channel 25 and supports a pivot bearing shaft 32 extending laterally therefrom. A gage plate 33 is mounted on the shaft 32. As shown in Figure 3, the plate 33 has bent-up flanges 34 with alined holes therethrough adapted to receive the shaft 32.

A gage 35 is movable relative to the plate 33. The gage is in the form of a post or staff slidably confined against the plate 33 by guides 36. The guides are secured to the gage plate by bolts 37 having spacer sleeves thereon. The upper end of the gage moves past a graduated scale 38. The scale is secured to the gage plate by bolts 39 passing through a slot 40 extending vertically of the plate 33.

A gage track 41 in the form of an upwardly extending plate having a horizontal upper edge is secured to a spacer plate 42 bolted to the rear flange of the channel forming the troweling member 16 of the screed. A clevis 43 secured to the lower end of the gage 35 has a wheel or roller 44 journaled thereon which bears on the track 41. By the construction and arrangement of the parts illustrated and described, it will be evident that the upper end of the gage 35 is positioned relative to the scale 38 in accordance with the elevation of the troweling member 16 of the screed at the point at which the gage track 41 is secured. As indicated by its position relative to the turn-buckle 17, the gage track is located adjacent the mid-point of the length of the screed. It will also be apparent that as the screed reciprocates the gage track moves with it. On such reciprocation, the track 41 travels below the wheel 44, the gage being maintained in vertical position by the guides 36 and free for vertical movement, without binding.

When the troweling member 16 of the screed is adjusted from a relatively straight to a curved condition by operation of the turn-buckle 17, the mid-portion of the member 16 is elevated since the ends thereof are maintained at a fixed elevation, i. e., in contact with the road rails, regardless of whether a flat or crowned slab is being finished. As the member 16 is arched or crowned, the gage rises accordingly and the position of the upper end thereof relative to the scale 38 indicates the magnitude of the crown, i. e., the ele-

vation of the mid-portion of the member 16 relative to the end portions thereof. The crown to which a pavement slab is finished is usually designated by the height in inches of the mid-portion of the pavement above the edges and the scale 38 may, therefore, be conveniently graduated in inches as shown in Figure 4.

It will be apparent from the foregoing that the invention is characterized by numerous advantages over screed indicators as known heretofore. In the first place, the fixed member of the indicator, i. e., the gage plate 33, is mounted on a fixed and relatively nondeformable structure, the frame of the finishing machine. The movable member, i. e., the gage 35, is positioned in accordance with the elevation of the mid-portion of the troweling member of the screed above the ends thereof which in turn depends upon the adjustment of the screed-flexing mechanism. The degree of arch or crown imparted to the screed is indicated directly by the position of the top of the gage 35 relative to the graduated scale 38 and these parts are so positioned as to be readily visible to the operator of the machine. Observation of the indicator is facilitated by the fact that the indicator does not oscillate with the screed but remains stationary. The accuracy of the indication, furthermore, is not affected by the reciprocation. The pivotal mounting of the gage plate provides accommodation for any slight back-and-forth movement of the screed and its support as a whole and prevents bending or binding of the gage 35.

The construction of the indicator of my invention is simple and relatively inexpensive. The indicator, furthermore, does not interfere with the normal operation of the finishing machine. Screeds such as that of the French patent, for example, are usually mounted so they can be lifted clear of the pavement and side rails for backward movement of the machine prior to a second pass over the slab being finished. Such operation is permitted by my indicator since it results merely in the gage moving upwardly above its normal position. This furnishes an indication to the operator, at a glance, whether the screed is raised or lowered, even though it is not in the direct range of his vision. The adjustability of the scale 38 makes it possible to calibrate the indicator readily, despite variations between different machines resulting from the usual manufacturing tolerances or any permanent deformation of the frame although the latter is not likely to occur.

Although I have illustrated and described but a preferred embodiment of my invention, it will be recognized that changes in the construction and arrangement of parts may be made without departing from the spirit of the invention or the scope of the appended claims.

I claim:

1. An indicator for a finishing machine including a main frame, a transverse screed and crown-adjusting mechanism for said screed, said indicator comprising a substantially vertical member secured to said frame and a gage movable relative thereto, and means mounted on said screed and moving therewith providing a horizontal bearing surface effective to support said gage in various positions, depending on the elevation of the screed at the point where said means is located.

2. An indicator for use on a finishing machine including a rigid, relatively non-deformable frame, a deformable screed extending transverse-

ly thereof, and means for deforming the screed to different degrees of curvature, said indicator comprising a gage plate supported on said frame, a gage movable along said plate, and a horizontal bearing surface on said screed supporting said gage in a position determined by the elevation of the screed at the point where said means is located.

3. An indicator for use on a finishing machine including a rigid, relatively non-deformable frame, a deformable screed extending transversely thereof, and means for deforming the screed to different degrees of curvature, said indicator comprising a gage plate supported on said frame, a gage movable along said plate, and a gage track on said screed, said gage resting on said track.

4. An indicator for use on a finishing machine including a rigid, relatively non-deformable frame, a deformable screed extending transversely thereof, and means for deforming the screed to different degrees of curvature, said frame being adapted to be supported on rails between which an area is to be paved, said indicator comprising a gage plate supported on said frame, a gage reciprocable vertically of said plate, and means on said screed providing a track support-

ing said gage in a position determined by the elevation of the screed at the point where said means is located, above said rails.

5. An indicator for use on a finishing machine including a rigid, relatively non-deformable frame, a deformable screed extending transversely thereof, and means for deforming the screed to different degrees of curvature, said indicator comprising a gage plate supported on said frame, a gage reciprocable vertically of said plate, and a gage track on said screed, said gage resting on said track.

6. An indicator for use on a finishing machine including a rigid, relatively non-deformable frame, a deformable screed extending transversely thereof, and means for deforming the screed to different degrees of curvature, said indicator comprising a relatively fixed vertical member, means pivotally mounting said member on said frame, a relatively movable gage cooperating with said vertical member to provide a visible indication, and means on said screed providing a track whereby said gage is supported in a position determined by the degree of deformation of the screed.

JAMES E. BUSHNELL.
